UNITED STATES PATENT OFFICE.

HERMANN MERKEL, OF ST. LOUIS, MISSOURI.

DESIGN FOR A HYDROCARBON-BURNER.

SPECIFICATION forming part of Design No. 32,105, dated January 16, 1900.

Application filed November 10, 1899. Serial No. 736,547. Term of patent 7 years.

To all whom it may concern:

Be it known that I, HERMANN MERKEL, a citizen of the United States, residing in the city of St. Louis, State of Missouri, have invented and produced a new and original Design for a Hydrocarbon-Burner, of which the following is a specification.

Figure I is a side elevation of a hydrocarbon-burner embodying my design. Fig. II is a top plan view.

As shown in the drawings, the leading or essential feature of my design for the hydrocarbon-burner consists of the portion 1, the cylindrical portion 2, extending upwardly from the portion 1, the cylindrical portion 3, extending upwardly from near the upper end of the portion 2 at an angle of substantially forty-five degrees, the cylindrical portion 4, extending in a horizontal plane crosswise of the upper end of the portion 3, the cylindrical

portion 5, extending upwardly from one end of the portion 4 in vertical alinement with the portion 2, the cylindrical portion thus extending upwardly from the portion 5, said portion 6 having the recesses 7 in its outer face near 25 its upper end, and the slits 8, extending upwardly from its upward end. The opening 9 extends through the portions 5 and 6 and is enlarged at its upper end to form the shoulders 10. The bead 11 is located between the 30 portions 5 and 6, and the bead 12 is located upon the upper end of the portion 4, and the eye 13 extends upwardly from the portion 3.

I claim—

The design for a hydrocarbon-burner substantially as herein shown and described.

HERMANN MERKEL.
